UNITED STATES PATENT OFFICE.

J. E. CULVER, OF HUDSON, NEW JERSEY.

IMPROVEMENT IN STEAM-GENERATING APPARATUS.

Specification forming part of Letters Patent No. 36,643, dated October 14, 1862.

To all whom it may concern:

Be it known that I, J. E. CULVER, of the city of Hudson, in the county of Hudson and State of New Jersey, have invented a new and useful Improvement in Apparatus for Generating Steam; and I do hereby declare that the following is a full, clear, and exact description of the same, reference being had to the accompanying drawings, forming part of this specification, in which—

Figure 1 is a central longitudinal vertical section of a steam-generating apparatus constructed according to my invention. Fig. 2 is a horizontal section of the same. Fig. 3 is a transverse vertical section of the same.

Similar letters of reference indicate corresponding parts in the several figures.

This invention relates to that class of steam-generating apparatus in which the gaseous products of the combustion of the fuel are allowed or caused to mingle with steam generated by heat transmitted from them to the water, and used in combination with such steam as a further source of motive power.

The principal object of the invention is to obtain a combination of the steam and gaseous products of combustion at as low a temperature as is possible, and thereby not only to obviate the difficulties attendant upon the use of steam and gases at a high temperature, but to generate the greatest quantity of steam attainable from the combustion of a given quantity of fuel; and the invention consists in a certain construction of the generating apparatus, and certain improvements in some of the details thereof to effect that result.

To enable others skilled in the art to make and use my invention, I will proceed to describe it with reference to the accompanying drawings.

A is the outer shell of the boiler, which may be of any known or suitable form.

B is the furnace, arranged within the shell A in such a manner as to be entirely surrounded and covered with water. The shell is made considerably larger proportionately to the furnace than when the steam alone is to be used as the motor. The furnace may be of any suitable form; but I prefer it to be of such form and so fitted with an internal fire-box, C, as to permit the air, which is supplied to the furnace under pressure by an air-pump or con-

denser, to pass from above downward through the fuel and the grate D to the ash-pit D', and thence to rise through passages f f outside of the fire-box, on each side thereof, as indicated by arrows in Fig. 3, to a space, g, in the top of the furnace, where the combustion is completed, and from whence the gaseous products are distributed through a system of submerged tubes or flues, E E, intercommunicating through every part of the boiler below the water-level before escaping into the water through numerous small orifices in the lowermost flues, and rising through the water into the steam-space in the upper part of the boiler. These flues should be of such form and so arranged as to extend from near the bottom to near the water-level, and nearly the whole length and width of the boiler, and to cause the circulation of the gases in numerous thin sheets or streams, with the interposition only of a metallic conductor of heat among the whole body of water in the boiler. The flues represented consist of two series of horizontal flattened tubes intersecting each other at right angles, as shown in Fig. 2, and a series of vertical tubes of similar form intersecting the said horizontal tubes; but the construction and arrangement of the flues may be varied, provided, always, that they be made to present sufficient surface to cause the surrounding water to absorb a sufficient quantity of heat from the gases to effect the reduction of their temperature to such a degree as to make it approximate to the temperature of the steam before the mixture of the two is allowed to take place in the upper part of the boiler.

In order to subdivide the bubbles in which the gases rise through the water, I arrange one or more diaphragms, d d, of wire-cloth or other reticulated or perforated material, in horizontal positions between, among, and around the flues, by which means I am enabled to more thoroughly mix the steam and gases.

M is a perforated diaphragm, dividing the portion of the fire-box above the grate into an upper and a lower chamber, the lower chamber being the fire-place proper, and the upper one an air-reservoir, from which the air supplied, as hereinbefore stated, is distributed equally to all parts of the ignited fuel on the grate.

The throat F, by which the upper part of the furnace is connected with the flues E E, is fitted with a valve, G, or stop-cock, operated by means of a rod, G', passing through a stuffing-box in the exterior shell, A, of the boiler, and intended to be closed by the fireman preparatory to the opening of the doors of the furnace, either to supply fuel or to remove ashes, for the purpose of preventing the escape of the gaseous contents of the furnace, the gases from the flues, and the water from the boiler. Several apertures may be provided in the furnace for the connection of the system of flues at several points, and each one must be furnished with a valve or stop-cock to be operated as and for the purpose above specified.

H is a passage leading through one side of the boiler into the fire-box and upper part of the furnace, for the supply of the fuel and the air for combustion. This passage is provided at its outer end with a door, I, which is fitted perfectly tight, and furnished with proper means of securing it in a closed condition at all times, but when it is necessary to introduce fuel, and is also provided at its inner end with a shutter, J, which can be closed to prevent the air from passing into the lower chamber of the fire-box and compel it to pass through an aperture, a, Fig. 3, into the upper chamber thereof, above the perforated diaphragm M, the said shutter J being worked by a rod, b, when the door I is open.

The pipe e, through which air is supplied, is represented in Fig. 3 as connected with the door I. It is, however, preferable to admit the air by a separate opening. The air-pipe must of course be closed to stop the supply of air before the valve G at the top of the furnace is closed.

K is a passage leading from the ash-pit through one side of the boiler, for the purpose of drawing out the ashes. This passage is also fitted at its outer end with a perfectly-tight door, L, which is only opened when it becomes necessary to remove the ashes.

The passages H and K are surrounded by water, which conducts away the free caloric from the hot gases which they contain when closed. The said passages may, however, be fitted with plugs composed of sheet-iron boxes filled with plaster, which, by occupying the spaces between them, exclude the gases, and so keep the doors I L comparatively cool.

N is a waste-pipe leading from within the flues E E, near the lowermost portion of the system, to permit a portion of the gaseous products of combustion to escape to the atmosphere without coming in direct contact with the water or mingling with the steam, whenever from any cause it is impracticable or not desirable to mix the whole of such products with the steam. This pipe is provided with a stop-cock, N', to regulate the escape or to close it entirely, when desired.

P is what I call a "safety-pipe," leading from the upper part of the furnace to the at-

mosphere, and furnished with a stop-cock, P', to be opened whenever the valve G at the top of the furnace is closed, for the purpose of allowing the escape of the gases of combustion to the atmosphere, but to be closed at all other times.

The operation of the generation of steam and the admixture of the steam with the gaseous products of combustion is as follows: The gaseous products traversing the submerged flues communicate their caloric through the metal of which they are composed to the water in the boiler, which surrounds them on every side. Simultaneously, by this means, the gases are cooled and the water heated, and steam is thereby rapidly generated between, among, and around them, as well as around the furnace, and by the time the gases issue from the orifices at the bottom of the flues their temperature has been so far reduced that the further cooling, to which they are subjected in rising through the water into the upper part of the boiler, where they mix with the steam, causes them to approximate in temperature to the steam before the mixture takes place. By the force of gravity the coolest portions of the gases will be caused to occupy the lowermost spaces in the flues, and the hottest the uppermost, meanwhile the continuous circulation of the gaseous currents through the flues contributes to the same result. It is evident that the more slowly the gases flow from the furnace to the water in the boiler—in other words, the longer they can be detained in the flues—the more they will be cooled in their descent, and the more nearly will their temperature at the instant of escaping from the openings of the flues approximate to that of the water into which they issue. Therefore the greater the aggregate capacity of all the flues, and the smaller and more numerous their ramifications, the greater must be the quantity of steam generated relatively to the amount of atmospheric air consumed, and the lower the temperature at which the mingled steam and gas can be used as a motive power. Again, by reducing the temperature of the gases to a suitable degree before their introduction into direct contact with the water, and causing their distribution among the water in a very divided state, the mixture of the air and gas is obtained in a sufficiently-moist condition to prevent any injury to the engine in which it is employed.

I do not claim the use of the gaseous products of combustion with steam generated by heat transmitted from these products to the water in the boiler; but

What I claim as my invention, and desire to secure by Letters Patent, is—

1. The combination, within the boiler, of a furnace, B, a system of submerged flues, E E, and one or more reticulated diaphragms, d, substantially as herein specified.

2. The furnace B, constructed with internal

fire-box, C, grate D, diaphragm M, air-inlet *a*, passages *f*/*f*, chamber *g*, and outlet F, the whole arranged substantially as and for the purpose herein specified.

3. The combination of the boiler A, furnace B, fire-box C, grate D, diaphragm M, air-inlet *a*, passages *f*/*f*, chamber *g*, outlet F F, and

flues E E, the whole constructed and arranged to operate substantially as herein specified.
